UNITED STATES PATENT OFFICE.

ANDREW J. SANFORD, OF NEWARK, OHIO.

DESIGN FOR A LIGHT-SHADE.

40,343.

Specification for Design.

Patented Nov. 9, 1909.

Application filed August 12, 1909. Serial No. 512,613. Term of patent 14 years.

To all whom it may concern:

Be it known that I, ANDREW J. SANFORD, a citizen of the United States, residing at Newark, county of Licking, and State of Ohio, have invented a new, original, and ornamental Design for Light-Shades, of which the following is a specification, reference being had to the accompanying drawing, forming a part thereof.

The drawing is a perspective view of a glass shade showing my new design.

The leading features of my design comprise a shade having a skirt or lower portion of substantially even flare, divided, as by

creases, into longitudinal sections. Each section has in the middle the figure of a conventionalized plant, and on each side thereof a series of prisms of symmetrical pitch. The shade has also a top portion of circular shape (as shown).

I claim:

The ornamental design for a light shade, as shown and described.

ANDREW J. SANFORD.
